UNITED STATES PATENT OFFICE.

HERMAN L. FELDBLET AND JOHN ROBERT O'DONNELL, OF NEW YORK, N. Y.

STAIR CONSTRUCTION.

1,427,276.

Specification of Letters Patent. Patented Aug. 29, 1922.

Application filed February 1, 1921, Serial No. 441,646. Renewed July 17, 1922. Serial No. 575,758.

To all whom it may concern:

Be it known that we, HERMAN L. FELDBLET and JOHN ROBERT O'DONNELL, citizens of the United States, residing in the city 5 and State of New York, have jointly invented an Improvement in Stair Constructors, of which the following is a specification.

The invention relates to a stair construction employing both structural steel and 10 structural reinforced concrete elements as carrying members, all so combined as to produce a more economical and otherwise more satisfactory fireproof stair than other existing types of all steel or composite structures.

Plain reinforced concrete stairs are made of ordinary concrete ingredients reinforced with steel bars and supported on a temporary wood form-work until the concrete has 20 attained sufficient strength to support itself across the span, at which time the wood forms are removed. This construction is costly, because of the nature of the forms necessary to support the wet concrete and 25 because of the heavy concrete slab and reinforcing required under the steps in order to supply the necessary strength.

The present invention recognizes the possibility of using a combination of structural 30 or pressed steel strings with inwardly projecting flanges, in conjunction with continuous monolithic reinforced concrete steps molded at opposite sides into the strings. In this way the steps are supported in part 35 by the flanges and in part by the continuous section of reinforced concrete beneath the treads. This continuous section of concrete connecting the steps together is materially thinner than the section required beneath 40 the risers in the plain concrete construction, and the internal reinforcing is also much lighter, so that the new construction is considerably less massive and less expensive.

The invention is further based upon the 45 recognition that by using these steel strings and designing the stair in the fashion described above, there is not only provided an economical design as far as the elements of the structure are concerned, but it also 50 comes possible to provide an economical means of attaching and supporting a flexible system of form-work, with which it is readily possible to handle different widths of stairs and different types of risers by mak-

ing simple adjustments in stock equipment. 55 The invention thus involves a combined structural steel and reinforced poured-in-place stair construction, in which the steel members, besides entering into the permanent structure, act as a part of the form-work, in conjunction with extensible riser-forms and floor-forms supported upon the strings, and preferably constructed substantially as hereinafter described.

In the accompanying drawings, forming a 65 part hereof:

Fig. 1 is a vertical longitudinal section through a portion of the form-work;

Fig. 2 is a top plan projection of a portion 70 of one of the strings, indicating also the end of one of the riser-forms;

Fig. 3 is a plan view of the form-work with the lower portion cut off in an inclined plane;

Fig. 4 is a section on the line 4—4 of 75 Fig. 1;

Fig. 5 is a section on the line 5—5 of Fig. 1;

Fig. 6 is a perspective view of one end of 80 one of the riser-forms;

Fig. 7 is a front elevation of a riser-form;

Fig. 8 is a vertical longitudinal section through a portion of the completed stair; and

Fig. 9 is a vertical transverse section on 85 the line 9—9 of Fig. 8.

The inclined strings 1 may be standard channel iron, pressed steel sections, or of a built-up section. They are disposed with 90 their lower and upper flanges 2, 3 projecting inward. Between these strings are supported riser-forms 4, and an inclined floor-form 5 is secured beneath them.

Movable triangular blocks 6 are secured at the inner sides of the strings beneath the 95 top flanges 3, being so designed and positioned as to lie in the angles between the treads and risers of the stairs to be constructed. As shown more particularly in Figs. 1, 4 and 5 the blocks are formed to fit 100 against the web and upper flange of each of the strings, and to be spaced at some distance from the lower flange.

An angular piece 7 has its vertical portion secured by fastenings 8 to the inner face of 105 each of the blocks 6 with its horizontal or laterally-extending portion 9 disposed at a distance above the block and projecting

outwardly so as to extend over the top of the flange 3. A set-screw 10, threaded through an opening in the said portion 9 to bear against the top of the flange, completes a 5 clamp whereby each movable block can be secured at any point along the string.

The vertical rear ends of the block 6 afford abutments for positioning and sustaining the riser-forms 4 against the forward 10 pressure of the concrete. For this purpose the rear inner corners of the blocks are preferably notched or recessed as indicated at 11 in Fig. 2, the depth of the recesses being equal to the width of the end portions 15 of the riser-forms, so that the backs of the latter are flush with the ends of the blocks. The end faces 12 of the riser-forms are advantageously beveled to fit correspondingly beveled opposed faces of the notches in the 20 blocks. The riser-forms are supported against dropping by top end projections 13, which rest upon the tops of the strings. These pieces are preferably angle members, comprising vertical and horizontal flanges 25 the edges of which are beveled to fit the sloping tops of the strings.

Each of the riser-forms is constructed of relatively movable sections, so that they can be set for various width of stair, and is also 30 flexible as to height. In the preferred embodiment, the form comprises a single panel section 14, which forms the recessed panel 14^a in the front of the riser of the concrete stair. In addition to this panel section, 35 each riser-form includes two front sections 15, which are movable longitudinally in opposite directions upon the panel section. The front sections extend beyond the ends of the panel section and also extend above 40 it. Bolts 16 projecting forward from the panel section, through horizontal or longitudinal slots 17 in the front sections, together with nuts 18 on the front ends of the bolts, afford means for holding the sections together while permitting the relative 45 movement. A vertical wedge 19, interposed between the proximate ends of the movable front sections, constitutes an expanding device whereby the front sections can be maintained at various degrees of horizontal 50 extension. The wedge may be retained in place by undercutting the inner ends of the sections 15 and preferably also by means of a keeper 24 extending across the front of 55 the wedge and supported by two of the bolts 16 at opposite sides.

Vertical extension is secured by the provision of means whereby the projecting end pieces 13 can be locked at various heights on 60 the sections 15, thus raising and lowering the bottoms of the riser-forms and permitting strips 20, see Fig. 1, to be added at the top. For this purpose the body portions 21 of the vertical portions of the pieces 65 13 which overlie the front faces of the sec-

tions 15 are shown provided with vertical slots 22 to cooperate with bolts and nuts 23 on the said sections. By utilizing a suitable number of the supplementary sections 20 the riser-forms can be built up to the desired height. 70

The riser-forms may be secured to the blocks 6 against rearward displacement by means of eyes 25 on the front sides of the end portions of the sections 15, registering 75 vertically with eyes 26 on the lower portions of the blocks to receive pins 27 which are dropped through the registering eyes.

The floor-form 4 may be of wood or metal, and is made in standard sections, so that 80 variable widths can be obtained. The sections of which it is composed are supported on cross-pieces 27, the ends of which extend beyond the sides of the form. The said ends are longitudinally slotted, as indicated at 28, to cooperate with hanger rods or bolts 29, which extend downward from the upper portions of the strings through the slots 28, beneath which they are provided with heads or nuts 30. Cross-brackets 31 are fixed to 90 the top portions 9 of the clamps of certain of the blocks 6. The opposite ends of these cross-brackets project respectively beyond the outer sides of the strings and the inner sides of the blocks, and are formed with 95 bolt-holes 32 adapted to receive the upper ends of the hanger rods 29. By tightening the nuts 30, 33 the cross-pieces 27 are clamped upward against the strings or against intervening spacing wedges 34. The 100 blocks 6 thus not only afford means for positioning and sustaining the riser-forms, but also furnish means for attachment of the floor-form. It will be understood that it is not necessary to connect hanger rods with 105 all of the blocks, as it will be sufficient to dispose the cross-pieces 27 at greater intervals. It is preferable to locate the hangers 29 at the outer sides of the strings, as 110 illustrated, but where conditions will not permit of this they may be engaged with the bolt-holes in the bracket pieces 31 at the inner sides, the hangers then passing through the floor.

With the form-work set up, reinforcing 115 rods 35 are arranged longitudinally above the floor and below the riser-forms, and other reinforcements 36 are arranged transversely. The concrete is then poured, and when in the proper condition troweled off 120 at the treads. When the concrete is sufficiently set, the block 6, the riser-forms 4 and the floor-form 5, with its transverse supports 27, are all removed, leaving the channel strings 1 and the monolithic reinforced concrete steps 36 cast therein and supported upon the bottom flanges, as illustrated in Figs. 8 and 9. The removal of the blocks 6 leaves recesses beneath the top flanges 3 in the angles between the treads 37 125 130

and risers 38, which recesses are preferably filled by inserting small concrete blocks 39.

We are aware that it has been proposed to make a stair of channel strings and pre-
5 cast cellular concrete step blocks. This, however, is an assembled construction and lacks the characteristics of our integral monolithic construction cast into the strings and having a continuous bottom section.

10. What is claimed as new is:

1. In concrete stair construction, the combination of strings having inwardly disposed flanges, said strings constituting part of the form-work and eventually entering into the 15 permanent construction, riser-forms supported by and between said strings, and a floor-form also supported thereby.

2. In concrete stair construction, the combination of strings having inwardly disposed 20 flanges, said strings constituting part of the form-work and eventually entering into the permanent construction, movable blocks secured at the inner sides of said strings, and riser-forms extending between the strings 25 and finding forward abutment support against said blocks.

3. In concrete stair construction, the combination of strings having inwardly disposed 30 flanges, said strings constituting part of the form-work and eventually entering into the permanent construction, movable blocks secured at the inner sides of said strings, riser-forms extending between the strings and finding forward abutment support against 35 said blocks, a floor-form, and means suspending said floor-form from said blocks.

4. In concrete stair construction, the combination of strings having inwardly disposed 40 flanges, said strings constituting part of the form-work and eventually entering into the permanent construction, movable blocks at the inner sides of the strings having clamps extending over the top flanges of the strings, riser-forms having forward abutment support 45 at their ends against said blocks, a floor-form, and hangers extending downward from said clamps to said floor-form.

5. In concrete stair construction, the combination of strings having inwardly disposed 50 flanges, said strings constituting part of the form work and eventually entering into the permanent construction, and means for sustaining forms in position on the strings comprising movable blocks at the inner sides of 55 said strings beneath the top flanges thereof and having parts extending over said flanges, and screws in said parts for clamping the blocks to the flanges.

6. In concrete stair construction, the combination of strings having inwardly disposed 60 flanges, said strings constituting part of the form-work and eventually entering into the permanent construction, and means for sustaining forms in position on the strings comprising movable triangular blocks adapted

to lie at the inner sides of the strings in the tread-and-riser angles, and having clamps for securing them to the strings.

7. In concrete stair construction, the combination of strings having inwardly disposed 70 flanges, said strings constituting part of the form-work and eventually entering into the permanent construction, and means for sustaining forms in position on the strings comprising movable blocks at the inner sides 75 and beneath the top flanges of the strings, and having clamps extending over said flanges.

8. In concrete stair construction, the combination of strings having inwardly disposed 80 flanges, said strings constituting part of the form-work and eventually entering into the permanent construction, movable blocks secured at the inner sides and beneath the top flanges of the strings, and extensible riser- 85 forms forwardly supported at their ends against said blocks.

9. In concrete stair construction, the combination of strings having inwardly disposed 90 flanges, said strings constituting part of the form-work and eventually entering into the permanent construction, extensible riser-forms supported by and between said strings a floor-form having supporting cross-pieces slotted at their ends, and fastenings between 95 the strings and the cross-pieces passing through said slots.

10. In concrete stair construction, the combination of strings having inwardly disposed 100 flanges, said strings constituting part of the form-work and eventually entering into the permanent construction, movable blocks secured at the inner sides of said strings, and riser-forms forwardly abutting at their ends against said blocks and having top end pieces 105 resting on the strings.

11. In concrete stair construction, the combination of strings having inwardly disposed 110 flanges, said strings constituting part of the form-work and eventually entering into the permanent construction, movable blocks secured at the inner sides of said strings, riser-forms forwardly abutting at their ends against said blocks, said forms being composed of relatively movable sections affording longitudinal adjustment, and top end pieces vertically adjustable on the relatively 115 movable sections to rest on top of the strings.

12. In concrete stair construction, the combination of strings having inwardly disposed 120 flanges, said strings constituting part of the form-work and eventually entering into the permanent construction, movable blocks secured at the inner sides of said strings, riser-forms forwardly abutting at their ends against said blocks, and angle pieces projecting endwise from the tops of the riser-forms to rest on the sloping tops of the risers.

13. In concrete stair construction, the combination of strings having inwardly disposed 130

- flanges, said strings constituting part of the form-work and eventually entering into the permanent construction, and riser-forms supported by and between said strings,
5 each of said riser-forms comprising a panel section at the back and a pair of front sections extending beyond the panel section and movable in opposite directions lengthwise thereon.
- 10 14. In concrete stair construction, the combination of strings having inwardly disposed flanges, said strings constituting part of the form-work and eventually entering into the permanent construction, movable blocks secured at the inner sides of said strings beneath the top flanges so as to occupy the angles between treads and risers, extensible sectional riser-forms extending between the strings in abutment with said blocks, and
15 20 means for supporting floor-forms of variable width from and beneath the strings.
- 15 15. In concrete stair construction, the combination of strings having inwardly disposed flanges, said strings constituting part of the
25 form-work and eventually entering into the permanent construction, riser-forms extend-

ing between the strings, a floor-form, cross-pieces beneath the floor-form, and fastenings between said cross-pieces and strings.

16. A riser-form for concrete stair construction comprising a panel section at the back, a pair of front sections extending beyond the ends of the panel section and longitudinally movable in opposite directions thereon, means holding the sections together and permitting such movement, and an expanding device between said front sections.

17. A riser-form for concrete stair construction comprising a panel section at the back, a pair of front sections extending beyond the ends of the panel section and longitudinally movable in opposite directions thereon, means holding the sections together and permitting such movement, an expanding device between said front sections, pieces on the remote ends of said front sections affording top end projections, and means for locking said end pieces to the front sections at different heights.

HERMAN L. FELDBLET.
JOHN ROBERT O'DONNELL.
